DESIGN FOR A BOTTLE OR SIMILAR CONTAINER

John B. Keightley, Los Angeles, Calif.

Application June 3, 1935, Serial No. 57,120
Term of patent 3½ years

To all whom it may concern:

Be it known that I, John B. Keightley, a citizen of the United States, residing at Los Angeles, in the county of Los Angeles and State of California, have invented a new, original, and ornamental Design for a Bottle or Similar Container, of which the following is a specification, reference being had to the accompanying drawing, forming a part thereof, in which

Fig. 1 is a perspective view of the bottle showing my new design.

Fig. 2 is a transverse horizontal section.

As is evidenced from the drawing, the bottle or jug is of elliptical form in transverse section and bears on one of its sides a pair of curved depressions provided with substantially vertical ridges.

I claim:

The ornamental design for a bottle or similar container, substantially as shown and described.

Signed at Los Angeles, Calif., this 24th day of May, 1935.

JOHN B. KEIGHTLEY.
